CLAIM

The ornamental design for a valve carriage, as shown and described herein.

DESCRIPTION

FIG. 1 is a right side view of a valve carriage showing our new design;

FIG. 2 is a left side view of the valve carriage.

FIG. 3 is a top view of the valve carriage.

FIG. 4 is a bottom view of the valve carriage.

FIG. 5 is a front view of the valve carriage.

FIG. 6 is a rear view of the valve carriage.

FIG. 7 is a top right rear perspective view of the valve carriage; and,

FIG. 8 is a bottom left front perspective view of the valve carriage.

The broken lines showing portions of the valve carriage form no part of the claimed design.

1 Claim, 6 Drawing Sheets**Related U.S. Application Data**

continuation-in-part of application No. 14/575,352, filed on Dec. 18, 2014, now Pat. No. 9,371,803, which is a continuation-in-part of application No. 14/043,157, filed on Oct. 1, 2013, now Pat. No. 8,944,101, which is a continuation-in-part of application No. 13/011,676, filed on Jan. 21, 2011, now Pat. No. 8,573,255, which is a continuation-in-part of application No. 12/749,924, filed on Mar. 30, 2010, now Pat. No. 8,584,704, application No. 29/554,814, which is a continuation-in-part of application No. 29/521,331, filed on Mar. 23, 2015, now Pat. No. Des. 750,746, which is a division of application No. 29/486,902, filed on Apr. 3, 2014, now Pat. No. Des. 728,747, which is a division of application No. 29/412,051, filed on Jan. 30, 2012, now Pat. No. Des. 706,390, which is a continuation-in-part of application No. 29/404,911, filed on Oct. 26, 2011, now Pat. No. Des. 706,389, which is a continuation-in-part of application No. 13/011,676, filed on Jan. 21, 2011, now Pat. No. 8,573,255.
